[57] ABSTRACT

A forced air oven is provided in which the air dispelled radially of the fan is directed by a bent elongate strip member forming a baffle mounted at the wall of the oven bearing the fan. By modification of the shape of the baffle, optimum heat distribution throughout the oven.

1
OVENS

This invention relates to ovens of the kind in which air is circulated in an attempt to provide an efficient and even heating of the contents. In particular, the invention relates to ovens which may be used for cooking or at least reheating pre-cooked food. However, such ovens may be used for other purposes. The oven may be heated in any known manner although gas and electric heating have been found preferable as accurate control of the amount of heat supplied to the oven is possible. Our British Pat. Nos. 1,183,202, 1,183,203 and 1,183,204 describe and claim ovens of this general kind.

Ovens of the kind referred to above are known as forced air ovens and the air which is circulated therein does not change and therefore there is no heat lost in heating fresh air from outside the oven.

It has been proposed to provide a forced air oven, suitable for use for catering purposes, which is gas heated. Such an oven has means for circulating air therein, a plurality of gas jets being adapted to heat the base of the oven, or at least an air space below the base, the air from such space first flowing through channels formed between increased outer walls of the oven and then escaping through a vent or chimney. In such an oven a fan driven by an electric motor circulates air so that heat is distributed throughout the oven. Unfortunately in some catering operations it is essential to have as little temperature variation as possible.

It is an object of the present invention to enable one to provide a forced air oven having good heat distribution over each of the trays used therein.

According to the present invention there is provided a forced air oven having a baffle mounted at the wall thereof bearing the fan, the baffle being formed of a bent or curved elongate strip member. The baffle should be mounted substantially symmetrically of a vertically downwardly extending segment from the centre of the fan, the lower part of the baffle being at a greater radial distance from the centre of the fan than the ends thereof and the baffle being mounted so as to present a main surface area thereof to air expelled radially from the fan, in use of the oven.

It has been found that the lower part of the baffle should be substantially level with the top of the bottom tray of the oven, if the best results are to be obtained. Best results have been obtained when wire, as opposed to sheet metal, shelves are used in the oven, since this facilitates air circulation (it being borne in mind, however, that generally the foodstuff being prepared in the oven will be on trays of sheet metal).

In a 25 15/16 inches internal width oven of the type marketed by ourselves, it has been found that good results are obtained by the use of a 1 1/4 inches wide baffle mounted 1/2 inch away from the back plate of the oven with the ends thereof 13 inches from the centre of the fan and the lower part thereof 13 1/2 inches from the centre of the fan.

For safety reasons, a screen of some sort must be provided in front of the fan. It is preferred to provide a wire mesh screen, by mounting a planar mesh on a frame which also carries the baffle in accordance with the invention. A 14 gauge, 1/2 inch mesh screen has been found to be satisfactory.

For a better understanding of the invention and to show how the same may more readily be put into prac-

2

tice, an embodiment thereof will now be described, by way of example, with reference to the accompanying drawings which show an example of oven fitted with a baffle in accordance with the invention, although the type of burner is not of importance as far as the present invention is concerned.

In the drawing,

FIG. 1 is a front elevational view, partly in section, of an oven according to this invention;

FIG. 2 is a side elevational view, partly in section, of the oven of FIG. 1;

FIG. 3 is a plan view of a metal mesh and associated parts of the oven;

FIG. 4 is a side elevational view of FIG. 3;

FIG. 5 is a perspective view of a frame used in the oven; and

FIG. 6 is a top view of the oven, with the cover removed.

An oven of the general kind described in our British Pat. No. 1,183,204, apart from the back plate 1 and baffle 2, is provided with a back plate 1 having a substantially rectangular cut-out 3 through which the fan 4 is mounted, with two circular cut-outs 5 for the provision of lighting in the oven. The sides 6 of the back plate 1 are bent forward to assist the circulation of air from the fan 4 around the oven in the usual way.

In front of the back plate 1 there is provided a wire frame 7. This wire frame 7 carries a planar metal mesh 8 in front of the fan 4 so as to form a safety screen for the fan 4. At the bottom of the wire frame 7 there is mounted a 1 1/4 inches wide metal strip 2 bent on a segment of a circle, with the ends 9 and 10 of the strip 13 inches from the centre of the fan 4 and the bottom 11 thereof 13 1/2 inches from the centre of the fan 4 (the oven being 25 15/16 inches wide and 24 inches high, internal measurements). The strip 2 is so mounted as to be 1/2 inch from the back plate 1. The strip 2 extends across approximately 17 1/2 inches of the back plate 1 of the oven. For different size ovens, the strip 2 will naturally be of slightly different configuration to provide optimum distribution of heat about the oven.

It has been found that with particular ovens different orientations, lengths and widths of baffle may be necessary to provide optimum results. However, using the "baked biscuit test" it is possible by trial and error to ascertain the details of baffle according to the invention required.

The forms of the invention herein shown and described are to be considered only as illustrative. It will be apparent to those skilled in the art that numerous modifications may be made therein without departure from the spirit of the invention or the scope of the appended claims.

What is claimed is:

1. A forced air oven having means for circulating air therein, a plurality of gas jets being adapted to heat at least an air space below the base of the oven, the air from such space first flowing through channels formed between outer walls of the oven and then escaping through a vent, the means for circulating air being a fan driven by an electric motor, a baffle being mounted at the wall of the oven bearing the fan and being formed of a curved elongate strip member, the baffle being mounted substantially symmetrically of a vertically downwardly extending segment from the centre of the fan, the lower part of the baffle being at a greater radial distance from the centre of the fan than the ends thereof, and in which the baffle is mounted so as to present a main surface area thereof to air expelled radially from the fan, in use of the oven.
